UNITED STATES PATENT OFFICE.

GEORGE CUMMINS, OF SAN ANTONIO, TEXAS.

DESIGN FOR A SMOKER'S CABINET.

49,013.

Specification for Design.

Patented May 9, 1916.

Application filed March 4, 1916. Serial No. 82,256. Term of patent 7 years.

To all whom it may concern:

Be it known that I, GEORGE CUMMINS, a citizen of the United States, residing at San Antonio, in the county of Bexar and State of Texas, have invented a new, original, and ornamental Design for Smokers' Cabinets, of which the following is a specification, reference being had to the accompanying drawing, forming part thereof.

The figure is a perspective view of the smoker's cabinet, showing my new design.

I claim:

The ornamental design for a smoker's cabinet, as shown.

GEORGE CUMMINS.

Witnesses:

J. B. FLANNERY,
T. H. FLANNERY.
